MOP

Harry Hertzberg, New York, N. Y.

Application June 15, 1932. Serial No. 617,267

7 Claims. (Cl. 306—11)

This invention relates to improvements in mops and holders therefor which may be used for a variety of different types of mops and dusters.

5 It is an object of the present invention to provide a mop holder which permits the mop held thereby to be placed in a plurality of different positions relative to the handle and to be rotated about an axis in each position.

10 It is a further object of this invention to provide a mop holder which permits the mop to yield in any of its various positions. It is a further object of this invention to provide a mop holder of soft and resilient material which 15 will not scratch or mar any object with which it may come in contact during the sweeping operation.

With these and other objects in view the invention consists in certain novel combinations 20 and arrangements of parts hereinafter more clearly described and finally pointed out in the appended claims and illustrated in the accompanying drawings in which—

Figure 1 is a plan view of a floor mop provided with my improved holder.

Figure 2 is a side elevation of my mop holder when attached to a mop and handle.

Figure 3 is a perspective detail of the mop holder plate before its attachment to a mop or 30 handle.

Figure 4 is a plan view of an oil mop provided with my improved holder.

Figure 5 is a sectional side elevation on line 5—5 of Fig. 4.

35 Figure 6 is a detail plan of the rear part of the plate 30 showing the means for tying the mop cloth thereto.

Figure 7 is a sectional detail on line 7—7 of Fig. 5.

40 Figure 8 is a sectional detail on line 8—8 of Fig. 6.

In the drawings, Fig. 1 illustrates a heart shaped mop head consisting of a plurality of wire strands 10 which are twisted about each 45 other and hold mop material 11 between them.

The wires 10 are bare of mop material in their middle part 10a which is covered by the mop holder and form symmetrical loops on both sides 50 of the handle 12 and a single loop in front thereof. The mop holder consists principally of a single elongated plate 20 shown in Fig. 3 which is preferably made from pure rubber properly vulcanized to be pliable and highly resilient. Plate 20 is provided near its middle portion with 55 two transverse ledges 21 so that between them

a deep groove 22 is formed across the center of plate 20. Near the outer sides of each ledge 21 two cylindrical projections 23 are formed on plate 20 which serve as distance pieces. The opposite ends of plate 20 are of semi-circular form and have apertures 24 in their centers. The mop handle 12 is preferably flattened at its end 12a as shown in Fig. 2, and provided with an aperture 13 therethrough. To fasten the mop head shown in Fig. 1 to handle 12 by means of plate 20 the portion 10a of the twisted wires 10 is placed into groove 22. The plate 20 is then bent into U-shape and the flat end 12a of the mop handle is inserted between the two circular end portions of plate 20. In this position the top faces of each couple of distance pieces 23 and 23a lean against each other and these pieces form a stop for the bottom end of mop handle 12 (see Fig. 2). A washer 14 is then placed against each of the opposite outer faces of plate 20 and a hinge pin 15 pushed through those washers, through the apertures 24 in plate 20 and through aperture 13 in handle end 12a. By means of a wing nut 16 which is threaded upon the end of pin 15 the ends of plate 20 can be drawn against the mop handle 12 and the latter be clamped tightly when it is swung on pin 15 into a desired angle. The two ledges 21 as shown in Fig. 2 lean against the wires 10a. When nut 16 is not tightly clamped 60 they and the mop with them may be rotated within the mop holder. But when nut 16 is tightened the ledges 21 clamp wires 10a tightly and the mop is held in fixed position. However the rubber parts of the mop holder permit a 65 yielding of the mop in any direction which gives the particular advantage that any object, as a piece of furniture when struck by the mop in sweeping, will not be injured by reason of the yielding action. It is of further advantage that the material of the mop holder itself is soft and yielding and will not injure an object which is struck thereby. In Figures 4 to 7, the application of the above described mop holder to an 70 oil mop is illustrated. This oil mop consists of a heart-shaped metallic plate 30 which is surrounded by a gutter 31 at its periphery which is formed by a vertical flange 32 and provided on its outward side with spaced teeth 33. A plurality of smaller apertures 34 are formed through plate 30 at the corner formed by flange 32 and gutter 31. The mop swab consists of mop cords 40 which are tied together in their middle portion by weaving them together at 41 and doubling the woven portions over a string or cord 42. 75

110

The mop swab and cord 42 are placed against the outside of flange 32 as shown in Fig. 5 and held in position by the teeth 33. The cord 42 is threaded through apertures 35 in flange 32 stretched tightly and bound to holding plate 36 provided on plate 30. In the middle portion of plate 30 an opening 37 is provided which is bridged by a rod 38 to which the mop holder hereinbefore described is attached, the rod 38 taking the place of the wires 10a for this purpose. In Fig. 5 the dotted lines indicate the positions into which the mop handle 12 may be placed relatively to the mop by swinging on rod 38. In Fig. 7, the dotted lines indicate the portions into which the mop handle may be placed by swinging it on hinge pin 15. It should be noted that the distance pieces 23 and 23a are pressed out of the way by the corners of the reduced portion 12a when rotating and snap back and press against the bottom of portion 12a as shown and hold the handle in such adjusted position or perpendicular to rod 38 when not clamped by nut 16.

By these simple means a very efficient holder is provided by which mops and other articles may be yieldingly secured to a handle and may be deflected and rotated about the axes perpendicular to each other.

Having thus described the preferred form of my improved mop and holder, it is to be understood that changes may be made in the arrangement of its parts and the construction of minor details thereof as come within the scope of the invention as claimed, without departing from the spirit of the invention.

I claim:

1. In a mop, a mop head, a handle and a flexible connection including two axes perpendicular to each other and to said handle, said connection joining said head rotatably to said handle by one of said axes and oscillatably by the second axis, said connection being formed of a single strip of pliable material as rubber to yield about both axes.
2. In a mop, a mop head including wire forming a part of said mop head, a handle, a rubberized connection for joining said wire to said handle, said connection consisting of a plate portion, spaced ledge portions formed integrally with said plate and adapted to grip said wire therebetween and clamping means for securing said head connection and handle together.
3. In a mop, a mop head including twisted wires for holding the mopping material, a handle, a rubberized connection for joining said head and

handle, said connection consisting of a U-shaped plate, spaced ledge portions formed integrally with said plate and adapted to grip said twisted wires therebetween, spaced lug portions disposed above said ledge portions and adapted to keep the legs of said U-shaped plate apart and to guide the handle into said connection and clamping means for securing said head, handle and connection together.

4. A holder for mops and the like consisting of a pliable plate bent U-shaped having a curved portion and a pair of flat parallel legs thereon, a mop handle having a flat portion interposed between said legs, a bar extending across one end of the handle and rotatable within the curved portion of said pliable plate, a bolt extending through said legs and said flat handle portion forming a pivot on which said holder may oscillate and means to press said legs against said flat portion.

5. In a mop, a mop head, a handle, a flexible connection between said head and handle comprising a U-shaped rubber plate having a curved portion and a pair of parallel legs thereon, a bolt on which said head may oscillate passing through said legs and handle, means on said bolt for clamping said legs against said handle, a bar on said head rotatably mounted in said curved portion and means on said curved portion engaging said bar when said clamping means are pressed against said legs.

6. In a mop having a handle and mop head, a connector for the mop head and handle consisting of a pliable plate adapted to be bent U-shape to provide a curved portion around one end of said handle and parallel legs leaning against opposite sides of said handle, a plurality of spaced lugs formed integrally with said plate and disposed on either side of the center of said plate, said lugs being oppositely in alignment with each other forming spacers for said legs when said plate is bent upon said handle.

7. In a mop having a handle and mop head, a connector for the mop head and handle consisting of a resilient plate adapted to be bent U-shape to provide a curved portion around one end of said handle and parallel legs to lean against opposite sides thereof, a bar on said head mounted in said curved portion, a pair of parallel ledges formed integrally with said plate transversely thereon on either side of its center and radially disposed within said curved portion for clamping said bar when said plate is bent upon said handle.
